UNITED STATES PATENT OFFICE.

LEONARD A. BELLONBY, OF HALDEMAN, KENTUCKY.

APPARATUS FOR CURING CONCRETE PRODUCTS.

1,264,142.

Specification of Letters Patent. Patented Apr. 30, 1918.

Application filed June 1, 1917. Serial No. 172,274.

To all whom it may concern:

Be it known that I, LEONARD A. BELLONBY, a citizen of the United States, residing at Haldeman, in the county of Rowan and State of Kentucky, have invented certain new and useful Improvements in an Apparatus for Curing Concrete Products, of which the following is a specification.

This invention relates to means for treating concrete or cement products, by the use of which the wet mixed concrete can be cured and removed from the mold ready for use in an extremely short time.

A further object of the invention is to provide an improved apparatus for carrying out this curing process, which is of extremely simple construction, which involves the use of but few parts of such construction as to be incapable of derangement or breakage, which involves but little expense in its maintenance, and which will prove thoroughly efficient in carrying out the objects of the invention.

With these objects in view together with others which will appear as the description proceeds, the invention resides in the novel formation, combination and arrangement of parts, all as will be described more fully hereinafter, illustrated in the drawings, and particularly pointed out in the claims.

In the drawings:

Figure 1 is a fragmentary sectional plan view taken through a curing plant embodying the invention,

Fig. 2 is an enlarged fragmentary sectional view illustrating the apparatus for filling or emptying the tanks or compartments,

Fig. 3 is a vertical sectional view taken through one of the tanks,

Fig. 4 is a view similar to Fig. 3, the section being taken at right angles through the tank,

Fig. 5 is an enlarged sectional plan view taken through one of the tanks and illustrating the heating coil, and

Fig. 6 is a view taken substantially upon line 6—6 of Fig. 3.

The method for obtaining the desired result, consists in placing the plastic material in suitable molds or containers, subjecting the material to dry steam, then immersing the plastic material in hot water, and lastly, subjecting the material to currents of heated air. The materials are subjected to the steam or vapor treatment for approximately

one half hour, and at the expiration of this time, the plastic material is immersed in water and the water boiled approximately three hours, and after the water has been drawn off, the plastic materials are subjected to currents of heated air for approximately thirty minutes. By thus treating the plastic material, the completed and properly cured concrete or cement products are produced at a great saving of time and expense, and it has been found in practice the products produced by this method possess the strength and durability of those produced by methods requiring many days for their completion.

The apparatus employed for carrying out this process comprises a plurality of tanks or compartments 5, within which the plastics are placed. It will be observed that each tank or compartment comprises vertical and right angularly disposed side and end walls, and the bottom 6 of each tank is provided adjacent one end with a depressed portion 7 which constitutes a gutter. The said sink or gutter affords means whereby the tank may be readily drained. In the present illustration, the tanks or compartments are illustrated as being formed of cement or other such material, but it will be understood, of course, that any desired materials may be used in the construction of the tanks.

Projecting upwardly from the bottom 6 of each tank and spaced a short distance from one of the end walls thereof, is a rib or short retaining wall 8, the latter forming one side of a shallow basin. This basin has disposed therein a steam heating coil indicated at 9, the said heating coil being so arranged within the basin that certain of the lengths of the coil will be submerged by water within the basin, while the remaining portions of the coil will protrude above the surface of the water. This heating coil may be supplied with steam from any suitable source.

Disposed in spaced parallel relation to the bottom 6 of the tank and a short distance above the uppermost coil of the steam heating agency, is a metallic plate 10, the said plate being supported upon suitable I-beams indicated at 11. This plate extends throughout the length and width of the tanks and is provided adjacent one end with an opening or aperture 12, through which steam or vapor generated from the water within the basin, or heat emanating

from the coil 9 may pass to the upper surface of the said plate. Arranged around the edges of the tank and projecting into the same a short distance are shelves or ledges 13, the latter being adapted to support trays or molds for the plastic materials to be treated, and these shelves are evenly spaced apart throughout substantially the entire height of the tank. The 10 lowermost shelf 13 is provided at its end remote from the opening 12 in the plate 10 with an aperture 14, while the next shelf above the said lower shelf is provided as at 15 with an aperture in substantially vertical alignment with the opening 12 in the plate 10. The shelves throughout the height of the tank are provided with alternately arranged openings or apertures, so that heat or steam generated at the base of the 20 tank must necessarily take a tortuous course in passing to the upper end of the tank. It will be understood, of course, that the central openings defined by the edges of the shelves 13 are to be closed by the trays or 25 containers for the plastic materials. One end of the tank is provided with a duct 16, the said duct extending throughout substantially the entire width of the end, and communicates at its upper end with the interior of the tank adjacent the uppermost shelf or ledge therein. This duct 16 constitutes a return for moisture or water at the upper end of the tank. It will be observed that this duct communicates at its 35 lower end with the interior of the tank a short distance above the bottom thereof.

Arranged preferably at an intermediate point between the various tanks or compartments 5 and below the bottom thereof 40 is a collecting pipe 17, the said pipe being utilized to control the flow of water to and from the various tanks. This collecting pipe 17 is relatively large, and has projecting outwardly therefrom a plurality of 45 smaller pipes 18, the latter communicating at their outer extremities with the interior of the tanks and within the basins upon the said tank bottoms. These drain pipes for the basins may be equipped with valves indicated at 19 in Fig. 1 of the drawings. The gutters of the tanks are also in communication with the collecting pipe 17, relatively short lengths of pipe 20 being employed, and each of these pipes 20 may 55 be provided with valves 21. A feed or steam pipe is indicated at 22, and this feed pipe may be provided with suitable branch pipes, each of which communicates with the lower end of the adjacent tank. Valves 23 60 are arranged in these various pipes, so that the flow of steam into the various tanks or compartments may be controlled. A conventional form of pump is indicated at 24, the said pump being in communication 65 with the drain and collecting pipes 20 and

17. By operating the pump, water may be directed into the tanks or may be removed therefrom, and it is obvious that by proper manipulation of the various valves, any one or all of the said tanks may be filled or 70 emptied.

In operation, the plastic material to be treated is placed in molds or trays, and the said trays are positioned upon the various shelves arranged in spaced relation throughout the height of the tank. Water is then supplied to the shallow basin at the bottom of the tank. A cover 30 formed of suitable material is then placed over the upper open end of the tank. The admission of steam to 75 the steam coil 9 causes the water in the shallow basin to become highly heated, and the steam or vapor thus generated rises and is superheated and partially dried by the exposed and highly heated portions of the steam 80 coil. The vapor passes to one end of the tank, and enters the lowermost mold compartment through the opening 12 in the plate 10. The steam then follows the course indicated by the arrows in Fig. 3 of the 85 drawings, and it will be understood that this steam enters the molds and intimately associates with the plastic therein. This steam or vapor treating operation is maintained the proper length of time, and gives to the 90 plastic material the initial set. Hot water is then pumped into the tank containing the plastic filled molds, and this water remains in the said tank a relatively long time. Steam continues to flow through the steam 95 coil 9, and the water within the tank is boiled and takes a tortuous course from the bottom of the tank to the top through the various apertures in the opposite ends of the shelves which support the plastic filled molds. This 100 water passes downwardly through the duct 16 at one end of the tank, and it is obvious therefore, that a constant circulation is maintained within the tank. At the proper time, this water is all drained from the tank, but 105 the heating coil 9 continues to operate. This operation of the heating coil, causes extremely hot air to be generated within the tank or compartment, whereupon a baking operation takes place. When this process is 110 completed, the molds may be removed from the tank to cool, and the cement or concrete products are ready for use.

By the employment of a process of this character, the plastic materials are thoroughly and adequately treated, and the products will be found to possess the required strength and durability. A plastic treating apparatus of this character may be used two or three times a day to produce the 115 desired article.

While the present is a disclosure of the preferred embodiment of the invention, it is to be understood that the invention is not limited thereto, as various changes in the 120 125 130

minor details of construction, proportion and arrangement of parts may be resorted to if desired without departing from the spirit of the invention as defined by the appended 5 claims.

What is claimed is:

1. In an apparatus for treating plastic materials, a tank, the said tank being provided at its lower end with a shallow basin, 10 a heating coil arranged partially within said basin, means for controlling the flow of liquid to and from said basin, a plate disposed across said tank above said heating coil, the said plate being provided with an 15 aperture, and the said tank being provided in one of its walls with a duct establishing communication between the interior of the tank at the upper and lower ends thereof.
2. In an apparatus for treating plastic 20 materials, a tank, a heating coil in said tank, shelves arranged in vertical alinement in the side walls of said tank, the said shelves being provided with openings arranged in staggered relation, and the said shelves being 25 adapted to support molds.
3. In an apparatus for treating plastic materials, a tank, shelves projecting into the

said tank from the walls thereof and being arranged in spaced relation to each other, one of the walls of said tank being provided 30 with a duct communicating at its upper end with the top surface of the uppermost shelf and at its lower end with the bottom of said tank, the outer edges of said shelves being adapted to support molds, the said shelves 35 being provided with openings arranged in staggered relation, and a heating unit in the bottom of said tank.

4. In an apparatus for treating plastic materials, a tank, the said tank being provided in its bottom with a gutter, a collecting pipe beneath said tank, branch pipes establishing communication between said gutters and the said collecting pipe, and a pump for causing water to travel in either 40 45 direction through said drain and branch pipes.

In testimony whereof I affix my signature in presence of two witnesses.

LEONARD A. BELLONBY.
